UNITED STATES PATENT OFFICE.

CHARLES E. GOSS, OF ROBERT LEE, TEXAS.

FAN ATTACHMENT.

1,180,916.

Specification of Letters Patent. Patented Apr. 25, 1916.

Application filed July 27, 1915. Serial No. 42,140.

To all whom it may concern:

Be it known that I, CHARLES E. Goss, a citizen of the United States, and a resident of Robert Lee, in the county of Coke and State of Texas, have invented a new and Improved Fan Attachment, of which the following is a full, clear, and exact description.

The prime object of my invention is to provide auxiliary fan blades attachable to a fan having permanent blades whereby to increase the fan surface, by attaching the auxiliary blades, or reducing the fan surface to its normal area by detaching the auxiliary blades.

The invention is more particularly intended for use in connection with the fan employed on the Ford car, although not limited to this particular use. I have found it effective with the Ford car in warm weather to increase the fan surface by additional blades, but the increased area would be undesirable in cold weather.

My invention therefore comprises means whereby the auxiliary blades may be readily attached or detached according to weather conditions, and it includes also means to hold the auxiliary fan blades against rattling when in position on the ordinary fan. The invention will be particularly explained in the specific description following.

Figure 1 is a face view of an ordinary fan employed on the Ford car; Fig. 2 is a face view of my attachable fan unit; Fig. 3 is a front view of the Ford fan with my attachable fan in position thereon; and Fig. 4 is a perspective view of a slight modification in which the attachable fan unit presents two fan blades instead of four, as shown in Figs. 2 and 3.

The Ford fan represented in Fig. 1 comprises four stationary fan blades *a* separately secured by fasteners *b* to the hub *c*, the securing bolt comprising a head *d*, extending through the hub.

My improved attachable fan in the form shown in Figs. 2 and 3 presents four radial blades 10 integral with a hub 11, in the form of a flat ring, the hub and fan blades being preferably stamped up from sheet metal.

At the base of each blade 10 a curved slot 12 is formed, the curve being struck from the center of the hub 11. A central hole 13 is formed in the hub 11 to permit the attachment to pass over the bolt head *d* (Fig. 1).

In applying the auxiliary fan to the ordinary fan, so that the respective blades will alternate as in Fig. 3, the auxiliary fan is passed over the bolt *d*, the hub 11 lying against the face of the hub *c*. The auxiliary fan is then given a turn through a sufficient angle for the stationary fan blades *a* to be received in the slots 12. The angular position of the blades 10 relatively to the hub 11 results in the inner portion of the blades 10 at the slots 12 passing to the rear of the stationary blades *a*.

In order to prevent rattling and insure that there will be no accidental displacement of the auxiliary fan, I provide in connection with one or more of the blades 10, a coil spring 14, one end of which is hooked through orifices 15 in the blades 10, the opposite end of the spring being formed with a hook which is engaged over an edge of an adjacent stationary blade *a*.

It will thus be seen that the efficiency of the stationary blade will be increased in proportion to the number of blades in the auxiliary fan, and improved cooling effects will be obtained in warm weather. On the other hand, when the additional blades would undesirably increase the cooling effect in cold weather, the auxiliary fan may be readily detached.

In the form shown in Fig. 4, the auxiliary fan is the same in all respects as that shown in Figs. 2 and 3, with the exception that but two blades 10^a are provided. The blades 10^a are formed on a hub 11^a similar to the hub 11, there being curved slots 12^a corresponding with the slots 12, and a central orifice 13^a corresponding with the orifice 13.

Having thus described my invention, what I claim as new and desire to secure by Letters Patent, is:

1. An auxiliary fan attachable to an ordinary fan to increase the effective surface thereof, said auxiliary fan presenting fan blades, and a hub, the hub having an opening adapting it to be passed over the securing bolt of the ordinary fan and there being curved slots at the bases of the blades, the slotted portions of the auxiliary blades being adapted to engage behind the blades of the ordinary fan when the hub of the auxiliary fan is turned through an angle in its own plane, and being adapted to be disengaged by a reverse turning movement.

2. An auxiliary fan adapted to be applied to an ordinary fan to increase the ef-

fective surface thereof, and comprising radiating fan blades and a hub in the form of a flat ring having a central opening adapted to pass over the bolt head of an ordinary fan and there being curved slots extending from an edge of each fan blade, the curves being struck from the approximate center of the hub.

3. An auxiliary fan attachment for ordinary fans to increase the effective surface thereof, comprising a hub having an axial opening and fan blades carried by said hub, said blades having means to engage the same with blades of an ordinary fan.

10 4. An auxiliary fan attachment for ordinary fans to increase the effective surface thereof, comprising a hub adapted to be secured in line with the hub of an ordinary fan and fan blades carried by said hub, a 20 coil spring secured at one end to a blade of the auxiliary fan, the said spring having a length and the opposite end thereof having means whereby it may be hooked over an edge of the blade of the ordinary fan.

15 5. The combination with a fan including fan blades, of an auxiliary fan presenting fan blades and a hub, said auxiliary blades having members at the base thereof engaging behind the blades of the first fan and 30 turnable through an angle to disengage the said members from said blades of the first fan.

6. The combination with a fan including fan blades, of an auxiliary fan presenting fan blades and a hub, said auxiliary blades having members at the base thereof engaging behind the blades of the first fan and 35

turnable through an angle to disengage the said members from said blades of the first fan, together with spring means forming a 40 connection between certain blades of the respective fans.

7. An auxiliary fan for attachment to an ordinary fan to increase the effective surface thereof, the blades of which auxiliary 45 fan are provided with means to detachably engage said blades directly with the blades of an ordinary fan.

8. A fan including a hub, fan blades thereon, and auxiliary blades in detachable 50 engagement with the first blades.

9. A fan including a hub, fan blades thereon, and auxiliary blades in detachable engagement with the first blades and adapted to be turned through an angle about the 55 axis of the fan and relatively to the said first blades to detach said auxiliary blades.

10. A fan including a hub, blades thereon, and auxiliary blades having a hub in the form of a ring and lying adjacent to the 60 hub of the first blades, the said auxiliary blades having curved slots in which the adjacent edges of the first blades are received, said auxiliary blades being turnable about the axis of the fan, through an angle to disengage the said auxiliary blades from the first blades.

In testimony whereof I have subscribed my name to this specification in the presence of two subscribing witnesses.

CHARLES E. GOSS.
